SAFETY PIN

Ernest V. Abbott, Chicago, Ill.

Application October 4, 1946, Serial No. 701,291

3 Claims. (Cl. 24—150)

1

This invention relates to improvements in safety pins.

One object of the invention is to provide a safety pin that normally is self-closing, that is, one so constructed that the pointed arm of the pin tends to move into a shielded position whereby if the pin is accidentally or inadvertently opened, it is less likely to free itself from the clothing and also less likely to injure the wearer. The pin, therefore, is particularly advantageous in fastening infant's wear.

Another object of the invention is to provide a safety pin provided with a shield for receiving the pointed arm when the pin is closed and a latch which engages the pointed arm within the shield and renders accidental or inadvertent opening of the pin extremely unlikely.

A further object of the invention is to provide a safety pin provided with a shield having therein a latch member for the pointed arm but the use of which latch member is optional with the user of the pin.

Other objects of the invention relate to various features of construction which will be apparent from the following specification and accompanying drawings, wherein

Figure 1 is a side elevation of a pin that is illustrative of the present improvements;

Fig. 2 is an enlarged side elevation of the pin shown in Fig. 1 but with the shield of the pin shown in section.

Fig. 3 is an elevational view of the pin shown in Fig. 2 looking to the left of Fig. 2;

Fig. 4 is a sectional view taken on line 4—4 of Fig. 2 showing the pointed arm in latched position; and

Fig. 5 is a view similar to Fig. 4 but showing the latch in a lateral position and the pointed arm in its normal spring retained position.

The pin shown in the drawings is formed of two parts, that is, a shield 10 and a pin body indicated generally by the numeral 11. The shield 10 may be formed of metal pressed or otherwise formed in the shape illustrated. In the form shown, the shield 10 is closed at the top and front and rear edges and at both sides except for a slot 12 formed in one side only. The pin body 11 is formed of a strip of resilient wire shown as provided with a coil 13 at the lower end which connects the relatively stationary arm 14 and the pointed arm 15. The upper end of arm 14 is shaped as shown in Figs. 1 and 2 to fit within the shield 10 and to provide an angularly disposed latch 16, the lower end of which constitutes a hook 17. The latch arm 16 as shown in Fig. 5,

2

normally extends somewhat laterally from the medial plane of the shield 10 whereby the hook 17 tends to assume a position wherein it extends laterally of the slotted wall 10a of the shield. The latch arm 16, at its lower end, normally contacts the forward wall 10b of the shield 10 and is sufficiently long to dispose the hook 17 below the lower edge of the shield. The shield and pin member 11 are secured together by any approved means such as by compressing the metal of the shield about the upper end of the relatively stationary arm 14 as indicated at 18 in Figs. 4 and 5.

The pointed arm 15 is not self opening but on the contrary, due to the coil spring 13, it tends to move to a closed position, that is, to the position shown in full lines in Fig. 2. However, the free end of the arm 15 cannot enter the shield unless pressed rearwardly into registration with the slot 12. Hence the arm, when the pointed end is not within the shield, tends to hold the pointed end against the shield. The arm 15 must be pressed outwardly, that is, in the direction of the arrow indicated in Fig. 1 to open the pin to enable the arm 15, shown in dotted lines in Fig. 1, to be inserted in the cloth to be pinned. After insertion of the arm 15 through the cloth to be fastened, the spring 13 tends to return the arm into position wherein the pointed end contacts the shield. Hence, should the pin, after insertion in the cloth, be not fully closed or should it be unlatched from fully closed position, it tends to retain itself in position in the cloth not only against loss but with the pointed end close to the shield 10 and therefore in a position less likely to injure the wearer. In closing the pin to fully latched position from the position of the arm shown in Fig. 5, the arm is moved to the left or against the action of the spring 13 and against the spring action of the latch 16 to the dotted line position shown in Fig. 2 in which position the pointed end of the arm 15 registers with the slot 12 in the wall 10a of the shield. The arm is then pressed through the slot into the shield and released whereupon the spring action of the arm 16, as well as the action of the coil spring 13, moves the pointed arm 15 into the full line position shown in Figs. 1 to 4, inclusive, wherein the pointed end contacts the inner face of the wall 10b of the shield.

In opening the pin, it is, of course, necessary to move the spring arm 15 toward arm 14 until the pointed end registers with the opening 12 whereupon the arm 15 can be shifted laterally through the opening 12 to the exterior of the shield. However, the spring arm does not then

spring to a fully opened position since the tendency of the spring is to retain the arm 15 in contact with the shield for the reasons of safety referred to above.

In the event the pin is to be used without utilizing the latch 16, the spring arm 15 may be moved laterally about the hook 14 and through the slot 12 and then released whereupon the spring 13 will move the spring arm to the right as viewed in Fig. 2 out of registration with the slot 12. The pin is not intended to be used without the latching feature and hence, but one side of the shield is provided with a receiving notch 12. The lateral extension of the hook is calculated to avoid closing the pin without engaging the hook since to close the pin without utilizing the latching feature, it is necessary to swing the pointed arm 15 laterally beyond the end of the hook in moving it to the slot 12. It will, therefore, be seen that in the normal closing of the pin it will be automatically latched since in so closing it normally, the pin engages the hook 17 which is disposed in the usual path of travel of the point toward the slot.

In Figs. 1 and 2 of the drawings, the coil 13 is shown disposed at the adjacent end of the arm 14 while the lower end of the arm 15 is provided with a rearwardly turned shank portion 15a that is connected integrally with the spring. This arrangement provides an arm 15 of a greater effective length since the coil 13 does not interfere with the movement of the cloth to the extreme lower end of the arm 15. Accidental pinching of cloth between the convolutions of the coil 13 is avoided in large measure by such arrangement although a conventional sheet metal guard may be pressed about the coil if desired.

While I have shown and described a pin structure which illustrates the invention, it will be apparent that changes in details may be resorted to within the spirit of the invention.

I claim:

1. A safety pin comprising a wire body and an arm integrally united at adjacent ends, the opposite end of said arm being pointed, a shield secured to the opposite end of said body comprising a receptacle for the pointed end of said arm, said shield having a slot in one wall thereof through which said pointed end is manually mov-

able, a resilient latch member in said shield integral with the adjacent end of said body and extending diagonally of the shield from the body to the opposed wall of the shield, and a hook 5 extending from said latch laterally of the shield for engagement by said arm as the same is moved toward and through said slot into the shield and urged by said latch against said arm for resiliently retaining the pointed end of the arm within the shield.

2. A safety pin comprising a resilient wire body section terminating at the upper end in a downwardly directed resilient latch member, a shield secured to said end of the body and enclosing said 15 latch member and provided with a recess in a side wall thereof, an arm pointed at one end, a biasing formation uniting the lower end of said arm to the lower end of said body and biasing the arm to a position wherein the upper end thereof is disposed adjacent said shield, and a hook member at the lower end of said latch projecting from said shield at one side thereof for engagement by the pointed end of said arm when the latter is moved into registration with and 20 through said recess whereby the latch and hook resiliently latch the pointed end of the arm within the shield.

3. A safety pin comprising a resilient wire body provided at the upper end with a downwardly and 30 forwardly directed resilient latch member and at the lower end with a biasing member, a shield enclosing said latch member and the upper portion of said body and having a recess in one side thereof, a hook extending from the lower end of 35 said latch member laterally beyond the recessed side of said shield adjacent the lower edge thereof, and a spring arm pointed at the upper end and integrally united at the lower end to said biasing member whereby the pointed end of the arm is biased normally into a position adjacent the exterior wall of said shield, said arm being 40 engageable with said hook for deflecting said resilient latch rearwardly as the arm is moved manually through said recess into said shield 45 whereby upon release of the arm the pointed end thereof is disposed in the shield between a wall thereof and said hook.
